DESIGN FOR A NUTCRACKER

George J. Moeller, St. Louis, Mo., assignor to Dazey Churn & Manufacturing Company, St.
Louis, Mo., a corporation of Missouri

Application October 5, 1938, Serial No. 80,271

Term of patent 14 years

To all whom it may concern:

Be it known that I, George J. Moeller, a citizen of the United States, residing in the city of St. Louis, State of Missouri, have invented a new, original, and ornamental Design for Nutcrackers, of which the following is a specification, reference being had to the accompanying drawing forming a part thereof, in which

Figs. 1, 2 and 3 are top plan, side and end views, respectively, of a nutcracker embodying my new design.

I claim:

The ornamental design for a nutcracker, substantially as shown.

GEORGE J. MOELLER.
